Primary Examiner — George D. Kirschbaum*Assistant Examiner* — Patricia K. Beard(57) **CLAIM**

The ornamental design for a stress relief toy, as shown and described.

DESCRIPTION

FIG. 1 is a front, top and left-side perspective view of a stress relief toy showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear, bottom and right-side perspective view thereof;

FIG. 9 is a perspective view thereof, shown in an alternate state; and,

FIG. 10 is another perspective view thereof.

The broken lines shown in the drawings illustrate portions of the stress relief toy that form no part of the claimed design.

1 Claim, 10 Drawing Sheets(56)
